UNITED STATES PATENT OFFICE.

ALONZO T. ADAMS, OF MARSEILLES, ILLINOIS, ASSIGNOR, BY MESNE ASSIGNMENTS,
TO MARSEILLES COMPANY, OF EAST MOLINE, ILLINOIS, A CORPORATION OF
ILLINOIS.

SPOUT.

1,031,829.

Specification of Letters Patent. Patented July 9, 1912.

Application filed December 10, 1909. Serial No. 532,311.

To all whom it may concern:

Be it known that I, ALONZO T. ADAMS, a citizen of the United States, residing at Marseilles, in the county of Lasalle and 5 State of Illinois, have invented certain new and useful Improvements in Spouts, of which the following is a specification, reference being had therein to the accompanying drawing.

10 My invention relates to spouts and particularly to grain spouts to be attached to the hoods of grain elevators or conveyers or the like or to cupolas or corn-cribs etc., to direct the material into the corn-cribs, 15 granaries, bins, cars, etc.

The invention consists in the matters hereinafter described and then pointed out in the claims.

In order to illustrate the construction and 20 a useful employment of my invention, I show the same in position upon a grain elevator or conveyer, although of course its use is not limited to such devices.

In the accompanying drawings. 25 Figure 1 is a side view of an elevator or conveyer provided with a spout constructed in accordance with my invention parts being broken away for purpose of clearer illustration; Fig. 2 is a longitudinal section view of certain parts of Fig. 1; Fig. 3 is a cross sectional view on the line 3—3 of Fig. 1; Fig. 4 is a view of one of the sections of the spout; Fig. 5 is a view showing positions of two sections of the spout when 35 being assembled or disassembled, and Figs. 6 and 7 are views of modified forms.

In the form shown the reference numeral 10 indicates a suitable elevator or conveyer, preferably for grain, seed, etc., provided 40 with a hood 11. The receiving hopper 12 of the spout is attached to the hood, and the hopper and upper spout-section or member 13 are jointed or connected together by any suitable swivel or rotatable connections 45 14 in a manner now well understood in the art whereby the spout may be turned or pointed in any direction away from the conveyer or elevator and at any desired curve or elevation.

50 The head-section or member 15 of the spout is pivoted as at 16 to the section 13, and like the succeeding sections or members 17 is preferably made half-round in cross-section or with an open top, and is provided 55 with flanges 18 at its sides. The sections

17 are connected to each other and to the head section by detachable joints. For this latter purpose the free end of the head-sections 15 and one end of each of the other sections 17 except the last is provided on its upper face with a flexible seat 19 formed by suitably shaping a leaf spring 20 near one end which is attached at its other end to the spout section as at 21, and the other end of each section 17 is provided with a collar 60 22 having upwardly projecting ears 23 adapted to enter eyes or openings 24 in the flanges of adjacent sections 15 and 17. Each spring is preferably flared or curved downwardly at its free end as at 25. 70

As shown in Figs. 6 and 7 I may provide means to hold the spring rigidly in place after it receives its band; for example I may use a thumb-screw 27 passing through the spring and engaging the associated 75 spout section or a bolt 28 on the spout and a thumb-nut 29 so that the spring is held in unyielding position.

When the spout is used it may be made any length desired by merely adding or removing the required number of sections. When a section is to be connected to the head-section 15, the ears 23 of the added section 17 are inserted in the eyes 24 of the head-section as shown in Fig. 5 and the section 80 17 is then slightly swung in the direction of the arrow in Fig. 5 to telescope its end over the adjacent end of the head-section and to bring its collar into place in the seat 19 of the spring of the head-section; other sections may be likewise added to obtain the desired length. The collar readily passes to its seat in the associated 85 spring as it rides over the flared end thereof and so presses the spring away from its section sufficiently to allow the collar to move into position, when the spring snaps into place over it and holds it against accidental displacement. The sections are thus readily and easily assembled upon the head-section and upon each other to any desired 90 length. The sections may be readily detached or disassembled by depressing or retracting the spring sufficiently to free its associated collar, when the corresponding section 95 may then be swung back to the position of Fig. 5 and its ears withdrawn from their associated eyes. 100

The ears are perforated as at 26 whereby suitable suspending wires or cables may be 110

attached to suspend the spout from the roof or rafters of the crib when desired. The interlocking of the collar and its ears on one section with the spring-seat and eyes of another section provides a rigid joint so that with any number of sections the spout is kept in a true line from end to end without sagging or bending under its own weight or under the weight of the material and will 5 be inclined uniformly from its upper or receiving end to its lower or discharge end when set at any angle or pitch. It is of course understood that in using the spout in a corn crib or granary the hood of the conveyer may 10 lead through an opening in the roof or the spout may be attached to the hopper-bottom of the crib cupola to which the conveyer feeds the material. By having a sectional or built-up spout it may be made long enough 15 in the first instance to discharge at the ends of the crib or bin and so fill the ends and partially fill the middle portion thereof, and then successive sections may be removed to permit the material to fill up the middle 20 portion to its full capacity. While the spout is primarily intended for use with ear corn, shelled corn, small grains, seed, etc., it may of course be used to handle other materials and in other locations.

25 30 The collar forms an offset or enlargement on the under side of the section to enter the seat of the spring in the associated section, and by the form shown the single piece of metal performs the function of this enlargement or offset and also forms the ears, although obviously these several parts may be varied as shown for example in Fig. 6. It is also obvious that the relative arrangement of the offset and its receiving spring 35 40 may be varied as to location and that various forms may be employed within the scope of my invention.

I claim:—

1. In a sectional knock down spout, a 45 pair of attachable and detachable telescoping spout members one of which is provided with a spring-seat and the other with an offset removably disposed in the seat in the first member, and supplemental detach-

able connections for said members, comprising an element on one member detachably and pivotally engaging a co-operating element on the other to allow the members to swing into and out of telescoping position to engage and disengage the spring-seat 55 connections.

2. In a spout, a series of attachable and detachable spout members having lateral flanges, each member provided with a spring seat near the lower portion of one end and 60 at the other end with an offset removably disposed in the seat of another member and with ears engaging the flanges of another member.

3. In a spout, a series of attachable and detachable spout members having lateral perforated flanges, each member provided with a spring seat near the lower portion of one end and at the other end with an offset removably disposed in the seat of 70 another member and with ears engaging the perforations of the flanges of another member.

4. In a spout, a series of attachable and detachable spout members substantially 75 half-round in cross-section and provided with lateral flanges having eyes, spring-seats on the lower portions of certain of said members, offsets on the lower portions of others of said members and ears on their 80 upper portions, the offset and ears of one member interlocking with the seat and eyes of another member.

5. In a spout a series of attachable and detachable spout members substantially 85 half-round in cross-section and provided with lateral flanges having eyes, spring-seats on the lower portions of certain of said members, collars on others of said members having ears at their upper portions, the 90 collar and ears of one member interlocking with the seat and eyes of another member.

In testimony whereof I affix my signature in presence of two witnesses.

ALONZO T. ADAMS.
